COMBINED LIQUID APPLICATOR AND
KINESITHERAPY DEVICE

Gottlieb Grossen, Washington, D. C.

Application May 5, 1938, Serial No. 206,223

4 Claims. (Cl. 128—65)

This invention relates to kinesitherapy, and especially to a kinesitherapy device by which the user's epidermis can be showered, rubbed, depressed and lifted or pulled by suction; so the device may properly be termed a combined liquid applicator and kinesitherapy device.

One object of the invention is to provide a device of this character that is useful and beneficial for any individual in taking a private bath, and which can be used by such individual for applying water or other liquid to every part of his or her epidermis, including that part between the shoulders which is impossible for some persons to reach with their hands, and which can be used on such parts for applying friction, pressure and suction, either simultaneously with the wetting or bathing, or alternately therewith, thus utilizing the applied liquid for an air-seal about the margin of each suction-cup, so as to render the action of the suction cups relatively easy and effective in their treatment of the epidermis.

Another object is to provide a device of this character that is useful for operatives at public baths, and for use of surgeons or physicians in the treatment of such diseases as neuritis, rheumatism, improper circulation of the blood, etc., by drawing blood to the surface, thus toning the skin and activating the internal organs for assisting proper elimination; also to assist in dissipating the fatty tissues for relief of obesity and over-weight.

A further object of this invention is to provide, in a unitary structure, one or more groups of flexible and resilient suction cups on an elongated body having a handle at each end, so the user can apply substantially equal pressure at all points on which the suction cups are pressed; also to provide the intermediate and main part of said body of such relatively narrow shape, with respect to its length, that such intermediate part can be grasped by the hand of an adult person so as to apply equalized pressure when only one hand is used in manipulating the device; so the said body may well be termed a handle-member.

Another object is to provide, in a device of this character, an improved form of liquid-container which is formed of two pieces of sheet material secured together at their edges or margins, one of these sheets being highly flexible and collapsible, while the other sheet is non-collapsible and only slightly flexible and has a group of friction-cups mounted thereon and conformable to curvatures of a person's body while remaining

in approximately fixed relation, to avoid being unduly tilted, so as to keep their entire marginal parts in contact with the epidermis while being moved thereupon from place to place.

Another object is to provide the handle-member with a group of suction cups on a substantially plane and inflexible side, opposite to the side on which the friction-cups are disposed, so the user can alternately and very quickly apply friction and suction to the epidermis while the latter is moist or wet from using the applicator.

Another object is to provide one of the handles of the handle-member with means that extends from its interior to its exterior for clamping or choking and releasing the liquid-supply tube that extends longitudinally therethrough to the liquid container that constitutes the principal part of the applicator.

Other objects and important features are pointed out or implied in the following details of description, in connection with the accompanying drawings in which:

Fig. 1 is a side-view of a device constructed according to this invention.

Fig. 2 is lower edge view, with respect to Fig. 1, a part of the liquid supply tube being broken off.

Fig. 3 is an enlarged sectional view taken along the line 3—4 of Figs. 1 and 2, viewed in the direction of the upper arrow, upper parts of the friction-cups being broken off.

Fig. 4 is an enlarged sectional view taken on the line 3—4 of Figs. 1 and 2, viewed in the direction of the lower arrow, the upper ends of the friction-cups being broken off, and the liquid container being partly collapsed.

Fig. 5 is a longitudinal sectional view of the handle-member having a part broken out, one handle detached and slightly spaced from the main portion, and the other handle having therein a part of the liquid-supply tube and a part of the tube-choking device.

Fig. 6 is an enlarged view of a portion of the pan which may (for the purpose of explanation) be considered as the lower section of the two-piece handle-member, this portion being a part of the handle which contains the choking device that interrupts the flow of liquid through the liquid supply tube, the bearing element being in section.

Fig. 7 is a transverse sectional view taken along the line 7—7 of Fig. 6.

Referring to these drawings in detail, in which, similar reference numerals refer to similar parts in the several views, the invention is described in detail as follows:

5 A main body or handle-member is formed of two pieces of rigid material which may be metal, hard rubber, Bakelite or molded plastic composition, the lower part 10 being a pan or pan-like member, and the upper part 11 being an open frame having an end-extension 11a that combines with the similar end-extension 10a to form a hollow handle; the parts 10 and 10a being united with the parts 11 and 11a, by screws, 10 rivets or other appropriate means, to form the unit that is herein known as the hollow handle-member, the part 11 forming an inwardly extending flange or retaining element around an opening 12 that extends the greater part of the 15 distances along and across the parts 10 and 11. The part 10 has therein a group of screw-threaded holes 13 to receive and hold screws 14 that hold suction-cups 15 in place and permit them to be removed when desirable. These suction-cups are flexible and resilient and of any appropriate size and shape, and have their open ends or margins substantially in the same common plane.

20 The liquid container is composed of a highly flexible and resilient sheet 16, rubber or the like, preferably molded into the shape shown in Fig. 3 and having its peripheral edge or margin clamped in an inwardly turned edge or margin of a sheet 17 that is of thin and slightly flexible 25 material such as metal, hard rubber, or one of the plastic resultants. This sheet 17 has a group of openings therethrough to receive eyelets or grommets 18 that extend through openings in the friction-cups 19 for securing the latter to 30 the plate or sheet 17 in open communication with the interior of the liquid container. The friction-cups 19 are of rubber or other flexible and 35 resilient material.

35 The lower part 10a of the handle-member is 40 preferably formed with a tubular bearing 20 through which the flexible and resilient liquid-supply 21 tube extends into the interior of the handle 10a—11a and thence into the parts 10 and 11 where it is united with the liquid container 45 as indicated at 22. The tube 21 also extends through a choking device that is secured in place by means of rivets or screws 23 that help to secure the parts 10 and 11 together. The choking device is composed of originally separate elements 50 24, 25, 26 and 27 in combination with an element 28 that may be either of the form shown or in the form of an inwardly turned lip of the sheet-metal member 24, this latter member having apertures to receive a pintle or pivot 26 on which the choke-lever 27 is pivoted. This lever 27 has a 55 long arm or handle 23' that extends out through the slot 29 and is operable to swing the short arm 30 into sliding contact with the flat springy arm 31 so as to press the hump 32 towards the element 28 for depressing and choking the inlet tube 21.

60 The handle 33 is preferably detachably secured in place by engagement of its stud-screw 34 in the screw-threaded socket 35 of the element 10.

65 *In operation.*—One or both handles are grasped by a hand or hands of the user who then first connects the inlet tube 21 to a water-faucet or other source of liquid supply, by the connecting socket 21a, opens the choking device by manipulation of the arm 28, then applies the friction-cups to the epidermis; and as the liquid 70 fills the container 16—17 and flows out through the outlet-openings in grommets 18 and through the friction cups 19, the latter are pressed and slid on the epidermis, by manipulation of the 75

user, so as to effectively wash and stimulate the epidermis, and if a further stimulation is desired, the flow of liquid is cut off by manipulation of the choke-lever, but the continued pressing and sliding of the cups 19 wipes the water or liquid from the epidermis while exerting a mild suction on each spot where one of the cups 19 is pressed and raised or slid, provided all the friction-cups are then closed; and next, if a stronger suction is desired, the device is turned over so that the suction-cups can be pressed upon and pulled from the epidermis. In pulling the suction cups 15 from the epidermis, a rolling motion or cant of the handle-member is facilitating.

While describing this form of my invention 15 specifically, I have no intention of limiting my patent protection to these precise details of description; for the invention is susceptible of numerous changes within the scope of the inventive ideas as implied and claimed. 20

What I claim as my invention is:

1. In a device of the character described, the combination of a casing comprising two opposed side members joined together to form a fluid container, one of said members being composed of 25 relatively flexible and resilient sheet material and the other of relatively rigid material, and friction cup members each provided with openings and secured to the latter member, said opening being in communication with the interior 30 of said container, and a housing enclosing one side of the fluid container with a wall adjacent the flexible member in position for engagement thereby when the casing is filled with fluid to provide resiliency for slight movement of the cup-carrying member relative to the casing. 35

2. In a kinesitherapy device, the combination of a flexible liquid container provided with an inlet for entrance of liquid thereto and also provided with a group of outlets, a relatively thin 40 and long handle-member having an open side including an inwardly extending flange around the opening of this side of the handle-member, said liquid container being confined in said handle-member by said flange while being free to be contracted from said flange and expanded towards 45 said flange, and a group of resilient flexible cups united with said flexible liquid container and in open communication with said outlets while protruding through said open side of said handle-member. 50

3. In a kinesitherapy device, the combination of a liquid container composed of a sheet of highly flexible material and a sheet of slightly flexible material united at their margins and provided 55 with a liquid-inlet, said sheet of slightly flexible material having a group of outlets therethrough, a relatively long and narrow and thin hollow handle-member having an open side including an inwardly extending flange around the opening of 60 this side of the handle-member, said liquid container being confined in said handle member by said flange while being free to be contracted away from the flange and expanded toward said flange, and a group of resilient flexible cups united with 65 said slightly flexible sheet and respectively in open communication with the interior of said liquid container through said outlets while protruding through said open side of the hollow handle member. 70

4. The combination defined by claim 2, and means in and extending from said handle-member, for interrupting the flow of liquid into said liquid container. 75
